UNITED STATES PATENT OFFICE.

FRANK D. BELKNAP, OF INWOOD, NEW YORK.

ADDRESSING-MACHINE.

SPECIFICATION forming part of Letters Patent No. 699,742, dated May 13, 1902.

Application filed February 15, 1900. Serial No. 5,306. (No model.)

To all whom it may concern:

Be it known that I, FRANK D. BELKNAP, a citizen of the United States of America, and a resident of Inwood, borough of Manhattan, 5 city, county, and State of New York, have invented certain new and useful Improvements in Addressing-Machines, of which the following is a specification.

My invention relates generally to stencil-printing machines, and more specifically to certain improvements in the card-feed mechanism of machines of this class designed for addressing envelopes, wrappers, &c.

In automatic addressing-machines it frequently occurs through defective feed mechanism that the cards in being advanced are crushed, mutilated, or otherwise injured or that two or more cards are fed forward at the same time. In consequence of such happenings the machine chokes up, and it becomes necessary to "shut down," clear away the wreckage, and prepare substitutes for the broken cards. This occupies the time of several operatives and constitutes an item of considerable expense, which it is the object of the present invention to avoid by simplifying and rendering the feed mechanism effective in successively advancing the stencil-cards, in properly presenting them in perfect condition for coöperation with the printing mechanism, and finally in providing for their delivery and storage when discharged from the machine.

A machine in its preferred form embodying my invention is illustrated in the accompanying drawings, throughout the several views of which like reference-numerals indicate corresponding parts.

Referring to the drawings, Figure 1 is a 40 sectional view in diagram, illustrating the automatic card-feed of a stencil-printing machine. Fig. 2 is an enlarged view in perspective looking toward the rear or delivery end of the machine shown in Fig. 1. Fig. 3 is a 45 view in perspective of one of the stencil-cards employed; and Fig. 4 is a detail sectional view of the card-receiving box, showing the inclined movable bottom frictionally sustained therein. Fig. 5 is a view in diagram, 50 illustrating the twin disk-feeding device in its relation to the card-magazines.

In the drawings, 1 represents a magazine

in which the stencil-cards are placed to be fed through the machine. The magazine consists of a trough-like box with open ends and is 55 bolted or otherwise secured to the frame of the machine at a proper angle and provided with a follower-weight 2, freely movable therein and placed in the rear of the cards for the purpose of advancing the latter to the feed 60 mechanism.

On a through-shaft 3, mounted in suitable bearings in the frame 4, twin disks 5 are keyed and are provided, respectively, with a series of equispaced peripheral teeth or projections 65 6 6, &c. These disks are arranged with respect to the card-chute so that the radial teeth are brought into operative relation with the frame 7 of the stencil-cards as the latter are advanced by the weighted follower, and 70 in rotation the cards are successively engaged by the teeth and fed into a second magazine formed by the guides 8. To prevent more than one card being fed forward at the same time, the entrance to the second magazine is 75 contracted by means of lugs 9, which project from the frame and partly overlap the guides, leaving only sufficient space for the passage of a single card. Twin strippers 10 are employed in connection with the disk-feed and 80 serve to insure complete disengagement of the disk-teeth from the cards as the latter pass from the curved into the horizontal portion of the magazine-guides.

11 represents the ink-fountain, which is arranged below the second magazine at a point beyond the disks, 12 being the fountain-roll thereof and 13 the ink-roll. The ink-roll is provided with a pad 14 and is geared to the fountain-roll, as indicated at 15. Above the 85 90 ink-roll and guides the platen or impression roll 16 is rotatably mounted and is cut away for a purpose to be described, leaving only sufficient surface to coöperate with the ink-pad. In the cut-away portion of the platen 95 an envelop-ejector is adjustably mounted, and consists of a curved strip 17, slotted at 18 and secured diametrically opposite the platen proper to its shaft by a screw 18^a, passing through the slot. The opposite ends 100 of this curved plate are bent up to form fingers 19 19, which project radially and are adjusted so that on rotation of the platen the fingers engage the printed envelop and throw

it clear of the machine into a box or other receptacle. (Not shown.)

The card-guides of the second magazine terminate at a point 20, just beyond the platen; 5 but the upper member or strip thereof is continued and bent downward at an incline, as indicated at 21. A pair of milled rollers 22 22 are employed, which coöperate with the inclined ends of the guides in effecting the dis- 10 charge of the cards into the receiving-box and are mounted on a shaft 23, suitably driven, their rotation being in the direction indicated by the arrow. After the stencil-card has passed between the platen and ink-roller it 15 is engaged and discharged into the receiving-box by the rollers above referred to.

24 represents the card-receiving box, which is vertically disposed and arranged at the discharge end of the machine to receive the 20 stencil-cards as they are delivered by the milled rollers. Within the box a movable bottom 25 is frictionally supported by means of a number of flat plate-springs 26, carried thereby, which bear against the walls of the 25 box. I preferably employ four of these springs to prevent binding of the bottom in its travel. As shown in Fig. 4, the bottom is inclined for the purpose of facilitating the entrance and packing of the cards. Within 30 the box on the wall adjoining the machine and near the top thereof a pair of bent strips 27 are secured and serve as guides in directing the cards when entering the chute and prevent their becoming entangled with the 35 moving parts of the mechanism. The rear wall of the box is cut away at 28, and at or near the upper end in the opening thus formed an oscillating packer 29 is mounted, which consists of a flat plate approximately U- 40 shaped and carried by a shaft 30, the shaft being mounted in bearings 31 31 and provided at its outer end with a crank-arm 32. Motion is transmitted to the packer from a central shaft 33 of the machine through the cam 34 45 and pivoted arm 35, which latter is provided at one end with a cam-roller 36, held in engagement with the cam 34 by means of a spring 37, and at its other end with a stud or pin 38, which engages a slot 39 of the crank- 50 arm 32. Twin guides 40 40 extend from the table downward at an incline and serve to carry the printed envelop when discharged by the ejector clear of the card-box.

Mounted on the table in operative relation 55 with the printing mechanism I have illustrated certain parts of a well-known envelop-feed mechanism, which, however, forms no part of the present invention and may be replaced by an automatic rotary newspaper- 60 wrapper cutter, such as is illustrated and described in Patent No. 581,259, of April 27, 1897, or the machine may be hand-fed or provided with any feed mechanism desired.

The operation is as follows: The stencil- 65 cards from which the addresses are to be printed are placed in the inclined magazine with the weighted follower in the rear, so as

to exert a constant pressure on the cards and cause them to be continuously forced toward the toothed disk. On starting the machine the 70 disks revolve and the teeth thereof in passing the open end of the magazine successively engage the frame of the cards and advance the same successively into the guides of the second magazine. As the first card passes 75 from the curved section into the horizontal portion of the guides the strippers act to insure a proper disengagement of the disk-teeth and the card is advanced toward the printing mechanism by the forward movement of 80 others in the rear fed through the continued rotation of the disks. An envelop is placed, either by hand or through the aid of suitable feeding mechanism, in position between the platen and the ink-roller, and as the card in 85 advancing in the guides is engaged by the rotating platen both the card and the envelop move forward and the printing is effected in the well-known manner. After being released the envelop is separated from 90 the card by the ejector and thrown outward upon the bent-wire guides 40 40, and the card is caught between the milled rollers and the inclined guide-terminals and discharged into the receiving-box, where it drops upon and 95 is supported by the inclined movable bottom. The packer is then caused to swing downward through the action of cam 34, which is adjusted to oscillate the same as each card drops into the box. When a card enters the 100 receiving-box, the packer on the downstroke exerts just enough pressure to overcome the springs and move the bottom downward a distance equal approximately to the thickness of the card. After a number of cards 105 have been discharged into the chute they tend to rise as the packer is elevated or returns to its normal position, but are checked in this tendency by the projecting lugs 41 41.

Prominent among the advantages of my invention may be mentioned the following: Through the employment of feed mechanism acting continuously and in one direction a comparatively slow motion in the operation thereof will advance the requisite number of 115 cards for serving a high-speed printing mechanism. At the same time under the action of the rotary feed, straight guides, and strippers the cards are brought to less wear and there is little or no liability of their being torn or 120 mutilated. Furthermore, by utilizing the cards in the receiving-box as a medium through which motion is transmitted from the vibrating packer to feed the frictionally-sustained bottom the available card-receiving 125 space varies as the number of cards entered, the entrance of the cards is facilitated, and the cards within the box are brought into compact relation.

It will be understood that I do not wish to 130 confine myself to the exact form or arrangement of parts herein described, as various changes may be made or equivalent mechanism substituted, involving a rearrangement

of parts or detail changes in adapting it to perform its intended function.

Having, therefore, described my invention, I claim as new—

- 5 1. The combination with printing mechanism and a card-magazine, of rotary card-feed mechanism, continuously acting and independent of the printing mechanism, said feed mechanism being operatively arranged between the magazine and printing mechanism, as specified.
- 10 2. The combination with printing mechanism and a card-magazine, of rotary card-feed mechanism continuously acting and separated from the printing mechanism, but operatively arranged to feed the cards from the magazine, as specified.
- 15 3. The combination with printing mechanism and a card-magazine, of rotary card-feed mechanism continuously acting, said feed mechanism being arranged between the magazine and printing mechanism to coöperate therewith as a separate and independent device.
- 20 4. The combination with printing mechanism and a card-magazine, of rotary card-feed mechanism continuously acting, said feed mechanism being arranged between the magazine and printing mechanism to coöperate therewith as a separate and independent device, and a second magazine, comprising card-carrying guides extending from the feed to the printing mechanism.
- 25 5. The combination with printing mechanism and a card-magazine of rotary card-feed mechanism continuously acting, said feed mechanism being arranged between the magazine and printing mechanism to coöperate therewith as a separate and independent device, and a second magazine, comprising card-carrying guides extending from the feed to the printing mechanism, the entrance to the second magazine being contracted to the approximate thickness of the card.
- 30 6. The combination with printing mechanism and a card-magazine, of rotary card-feed mechanism continuously acting, said feed mechanism being arranged between the magazine and printing mechanism to coöperate therewith as a separate and independent device, strippers for the cards and a second magazine, comprising carrying-guides extending from the feed to the printing mechanism.
- 35 7. The combination with printing mechanism and a card-magazine, of rotary card-feed mechanism continuously acting, said feed mechanism being arranged between the magazine and printing mechanism to coöperate therewith as a separate and independent device, and comprising a series of projections radially disposed about and carried by a rotatable shaft.
- 40 8. In a stencil-printing machine, the combination with card-magazines and stencil-printing mechanism of a stencil-card-feeding device, comprising twin disks, toothed to en-

gage the cards and arranged in operative relation to the magazines, one of the magazines extending from the point of feed to the printing mechanism, as specified.

70 9. In a stencil-printing machine, the combination with card-magazines and stencil-printing mechanism of a card-feeding device, comprising twin disks, toothed to engage the cards and arranged in operative relation to the magazines, and card-stripers coöperating with the disks, as specified.

75 10. In a stencil-printing machine, the combination with card-magazines and stencil-printing mechanism, of a card-feeding device, comprising twin disks, toothed to engage the cards and arranged in operative relation to the magazines, one of the magazines extending from the point of feed to the printing mechanism, and card-stripers coöperating with the disks.

80 11. In a stencil-printing machine, the combination with a vertically-disposed card-receiving box arranged in operative relation to the discharge end thereof, of a movable inclined bottom frictionally sustained within the box and an automatic feed for adjusting the bottom according to the number of cards entered, as specified.

85 12. In a stencil-printing machine, the combination with a vertically-disposed card-receiving box arranged in operative relation to the discharge end thereof, of a movable bottom frictionally sustained within the box and an automatic feed for adjusting the bottom according to the number of cards entered, and one or more projections entering the box as card-retainers, as specified.

90 13. In a stencil-printing machine, the combination with a vertically-disposed card-receiving box arranged in operative relation to the discharge end thereof, of a movable bottom frictionally sustained within the box, a series of springs secured to the movable bottom and bearing against the inner walls of the box, whereby the bottom is frictionally supported, and an automatic feed device for adjusting the bottom according to the number of cards entered, as specified.

95 14. In a stencil-printing machine, the combination with a card-receiving box arranged in operative relation to the discharge end thereof, of a movable bottom frictionally sustained within the box, a series of springs secured to the movable bottom and bearing against the inner walls of the box, whereby the bottom is frictionally supported, and an automatic feed device for adjusting the bottom comprising a vibrating arm relatively disposed to engage the cards within the box and suitable gearing for transmitting the requisite motion for vibrating said arm, as specified.

100 15. The combination of a rotary printing mechanism, a rotary stencil-card-feed mechanism separate from the printing mechanism, and straight slotted guides extending from

between the two and tangential to all the rotating elements comprised therein.

16. The combination of a continuously-rotating, printing mechanism, a continuously-rotating stencil-card-feed mechanism, and two oppositely-arranged slotted guides between which the card passes from feed mechanism to printing mechanism, whereby said cards are positively held in line at every point of

their progress from feed to printing mechanism.

Signed by me at New York, N. Y., this 8th day of February, 1900.

FRANK D. BELKNAP.
